UNITED STATES PATENT OFFICE.

CHARLES W. MERRIFIELD, OF SPRINGVALE, MAINE.

FLY-KILLER.

1,030,004.

Specification of Letters Patent. Patented June 18, 1912.

Application filed February 6, 1912. Serial No. 675,809.

To all whom it may concern:

Be it known that I, CHARLES W. MERRIFIELD, a citizen of the United States, and a resident of Springvale, Sanford, in the county of York and State of Maine, have invented a new and useful Improvement in Fly-Killers, of which the following is a specification.

My invention relates to fly-killers and its object is to provide a device of this character that has the same construction on both sides, and will not crush the flies, scratch any surface, or break glass.

My invention will be described in connection with the drawings which accompany and form a part of this specification in which—

Figure 1 is a plan view with certain parts broken away, and Fig. 2 is a section on the line 2—2 of Fig. 1.

In the particular drawings selected for more fully disclosing my invention, 1 represents a handle of any suitable form terminating in or provided with the prongs 2, 2. In the present instance the handle is formed of twisted wire and the ends thereof constitute the prongs.

The flap 3 consists of a double thickness of wire mesh or other suitable material, and in the present instance two pieces of wire mesh are placed on either side of the prongs and secured thereto by the caps 4, 4, which may be of leather or other flexible material. The reinforcing caps extend beyond the end of the prongs, and as shown in the present case, each is fastened to one of the prongs by the thread 4' which is then bound around the apex of the prong as shown at 4'' to prevent the prongs from spreading. The edges of the wire mesh may be bound with

any suitable material 5, such as leather, corduroy, etc., the inner edges of such binding material being sewed together and to the mesh, as shown at 5' and inclosing the reinforcing caps. It will be obvious that by 45 extending the caps beyond the ends of the prongs the latter are effectively prevented from breaking through the mesh and the binding when the device is in use.

By means of the construction above described, I am enabled to eliminate the usual wire loop which heretofore has been employed to inclose the mesh, thereby greatly increasing the flexibility of the device. It is because of such increased flexibility that 55 the reinforcing caps are desirable as otherwise, by the constant backward and forward bending of the plate, the ends of the prongs will break through the wire mesh.

It will be understood that various changes 60 may be made in the details of the device as described and shown without departing from the spirit of my invention.

I claim:

A fly-killer comprising a handle terminating in two prongs, a flap consisting of wire mesh secured thereto, reinforcing caps of flexible material secured to said prongs and mesh, said caps extending beyond the ends of said prongs for preventing the 70 latter from breaking through said wire mesh, and a binder for the edges of said mesh, said binder inclosing said caps.

In testimony whereof, I have hereunto subscribed my name this 3rd day of February, 1912.

CHARLES W. MERRIFIELD.
